UNITED STATES PATENT OFFICE.

EDWIN B. STIMPSON, OF BROOKLYN, NEW YORK.

DISTENDING-SPRING FOR LEGGINS.

SPECIFICATION forming part of Letters Patent No. 505,906, dated October 3, 1893.

Application filed December 2, 1891. Serial No. 413,845. (No model.)

To all whom it may concern:

Be it known that I, EDWIN B. STIMPSON, of Brooklyn, in the county of Kings and State of New York, have invented a new and useful Improvement in Distending-Springs for Wearing-Apparel, of which the following is a specification.

My invention relates to an improvement in distending springs for wearing apparel and more particularly to springs for holding a protecting article, such for example as leggins, in shape, and preventing them from collapsing and injuring the free circulation of blood through the parts of the body about which they are worn.

A practical embodiment of my invention is represented in the accompanying drawings in which—

Figure 1 is an edge view of the spring showing its ends fastened together. Fig. 2 is a face view of the same. Fig. 3 is a longitudinal section through the fastening and Fig. 4 is a transverse view through the fastening on line xx of Fig. 2.

The spring consists of a spring metal band having one of its ends provided with a tongue and the other end with a recess or guide way for the reception of the tongue of the opposite member, the tongue end carrying a spring actuated swinging link adapted to engage the recessed end and lock the ends together. The tongue and spring at one end and recess or guide at the other end are preferably formed integral with the body portion of the spring and the link is formed separately and secured permanently to the tongue end.

The body portion of the spring is denoted by A. At one end there is formed a projecting tongue B the sides b of which extend outwardly or forwardly from the surface of the body portion and the outer face b' of which is preferably formed concave in cross section. An actuating spring is formed by partially severing a portion C of the face b' of the tongue B and forcing its free end to assume a normal position below the face b' . The opposite end of the body A is provided with a recess or guide way D for the reception of the tongue B, the sides d of said guide way extending outwardly from the surface of the spring and its face d' being formed concave in cross section to conform to the face b' of

the tongue. The outer face of the guide way D is provided with a series of notches d^2 along its edges for the reception of the locking link E. 55

The locking link E is of a general U shaped form, the branches being inserted down through perforations b^2 in the tongue end of the spring, and thence turned obliquely toward the under face of the spring C and caused to bear 60 against it so that the tension of the spring C tends to press the bight e' of the link down into position to engage the notches d^2 . A projection e^2 on the end of the link E serves to receive the end of the finger to lift the link 65 out of engagement with the notches and thereby release the ends of the spring.

The normal tension of the spring band A is preferably such as to hold it partially straightened and its ends separated. 70

The concave face of the guide way serves to admit the finger under the projection e^2 on the link without catching in the notches d^2 , and the link is required to project beyond the face of the fastening only a slight distance, 75 affording little or no opportunity for catching in adjacent fabrics and presenting a compact and neat appearance.

The entire distending spring and its fastening may be formed of but two pieces and may 80 be adjusted within the limits of the series of notches d^2 .

What I claim is—

1. A spring band which tends, normally, to expand, having its ends provided, the one 85 with a guide way extending back from its end lengthwise of the band, and the other, with a tongue adapted to slide along within said guide way, and a swinging spring actuated link mounted in the end of the band carrying 90 the tongue and adapted to engage notches in the upper face of the guide way carried by the other end of the band, substantially as set forth.

2. The combination with a spring band, of 95 a fastening device for the ends of the same, said fastening device comprising two interlocking sections, the one provided with a guide way having a concave or depressed outer face, as described, and rows of notches along its 100 respective edges, the other provided with a tongue adapted to slide within said guide way and having an actuating spring formed on the inner face of same, and a locking link extend-

ing through apertures at the sides of the tongue and turned into engagement with the said actuating spring, the bight of said link taking over and elastically engaging the 5 notches in the guide way, whereby room is provided for the finger between the rows of notches for taking under and lifting said link.

3. The spring band having its ends developed the one into a tongue and actuating 10 spring and the other into a guide way for the tongue and provided with a series of notches,

and a link having its sides extended through the tongue end of the band into engagement with the actuating spring, and its bight or outer end constructed to engage the notches 15 in the face of the guide way, substantially as set forth.

EDWIN B. STIMPSON.
